GEORGE J. MEUER, OF MILWAUKEE, WISCONSIN, ASSIGNOR, BY MESNE ASSIGNMENTS,
TO CUTLER-HAMMER, INC., A CORPORATION OF DELAWARE

ELECTRIC SWITCH

Application filed May 31, 1928. Serial No. 281,890.

This invention relates to improvements in electric switches.

An object of the invention is to provide a switch having a minimum number of parts which are so designed as to facilitate production and assembly thereof.

Another and more specific object is to provide an improved form of pivotal connection between the movable contactor of the switch and the supporting frame.

Another object is to provide improved toggle actuating means for the switch, together with novel means for limiting the degree of movement of the actuator in opposite directions respectively.

Another object is to provide improved spacing means for the resilient stationary contacts of the switch.

Other objects and advantages of the invention will hereinafter appear.

The accompanying drawings illustrate my invention as embodied in a toggle lever actuated surface snap switch, but it is to be understood that certain features of the invention are likewise applicable to other types of electric switches, such as push button actuated switches for either flush mounting or surface mounting, etc.

In the drawings, Figure 1 is an enlarged top plan view of a toggle lever actuated surface snap switch with the cover member removed and with the stationary contact and its terminal member at the upper left hand side of the base removed for purposes of illustration.

Fig. 2 is a view, partly in side elevation and partly in vertical section on the line 2-2 of Fig. 1, with the cover member in position.

Fig. 3 is an enlarged fragmentary top plan view of a portion of the base, with one of the stationary contacts and its clamping terminal plate secured thereto.

Fig. 4 is a detail view showing the metallic frame member in vertical section and the movable switch contact in side elevation, and

illustrating in dotted lines a temporary position of the latter during assembly thereof with the former; certain elements of the switch actuating mechanism having been omitted to clarify this feature of the invention.

Fig. 5 is a perspective view of the metallic frame, movable contactor and actuating means for the latter assembled as a unit preparatory to attachment thereof to the insulating base.

Fig. 6 is a view, partly in side elevation and partly in perspective, of the several parts illustrated in Fig. 5 prior to assembly thereof.

Fig. 7 is a plan view of a relatively thin metallic blank or stamping from which each of the stationary contacts of the switch may be formed.

Fig. 8 illustrates the manner of forming two of the stationary contacts of Fig. 1 from blanks such as illustrated in Fig. 6,—the other two stationary contacts being formed from like blanks but having the projecting arms thereof bent in the opposite direction.

Fig. 9 is a side elevation of the contact shown in Fig. 8.

Fig. 10 is a top plan view of one of the clamping terminal plates illustrated in Figs. 1, 2 and 3 and showing the usual terminal screw applied thereto.

Fig. 11 is a fragmentary view, partly in section and partly in side elevation, illustrating a modified form of spring toggle connection between the toggle operating lever and the movable contactor of the switch, and

Fig. 12 is a plan view of the blank from which frame is formed.

Referring to the drawings, the numeral 15 designates a base formed of any suitable insulating material such as porcelain, or any of the various other types of plastic composition material. As shown the base 15 is provided with a centrally located substantially rectangular recess or cavity 16 within which

the movable contactor 17 of the switch is adapted to oscillate. Said contactor 17 is preferably supported by a frame 18 which is substantially of inverted U-shape in cross section, said frame having the end portions 19 and 20 of its arms bent at substantially right angles thereto to provide supporting feet for attachment to the base 15.

Thus the end portions 19 and 20 are provided with tapped openings 21 and 22, respectively, for cooperation with the shanks 23 and 24 of attaching screws the heads of which (not shown) are located in suitable countersunk openings in the lower surface 15 of the base. As will be understood the frame 16 is preferably formed from a single metallic blank (Fig. 12) having a perforation 25 adapted to provide an opening for the switch operating lever when the blank is bent to the form illustrated in the other figures of drawings.

Said blank is also provided with a pair of oppositely arranged substantially rectangular openings 26 and 27, which are so disposed that upon final formation of the frame 18 one portion of each of said openings extends vertically and another portion of each of said openings extends horizontally as best illustrated in Figs. 4 and 5.

I have indicated in dotted lines in Fig. 12 the points at which the blank is bent in forming the frame, it being noted that the vertical arms 28 and 29 are connected only by the integral cross pieces 30 and 31. Said arms are likewise provided with slightly curved projections 32 and 33 which are perforated, as indicated at 34 and 35, respectively, to receive a pivot pin 36.

The pin 36 is adapted to penetrate a pivot opening 37 in a flat sheet metal stamping 38. As best shown in Fig. 6 said stamping 38 is of substantially triangular contour, and the same is provided with a projecting upper end portion 39 of irregular contour to provide an interlocking connection between the same and the insulating material 40 molded thereabout which forms the operating handle of the switch. As shown in Figs. 1 and 5 said insulating handle is of sufficient width to provide a fairly close fit thereof between the arms 28 and 29 of frame 18, whereas sufficient clearance is provided around the opening 37 to facilitate insertion of the pivot pin 36.

The opposite ends 41 and 42 of stamping 38 extend outwardly beyond the lower edge of the insulating handle, and the upper surfaces of these end portions are adapted to engage the lower surfaces of the cross pieces 30 and 31 of the frame 18 to limit the oscillating or pivotal movement of the handle.

The stamping 38 is also provided with a depending projection 43 having a rounded end 44 adapted to engage in a socket formed by the flared upper end 45 of a tubular member 46; said flared end 45 being also adapted to

insure proper positioning of member 46 within the upper end of a coiled spring 47.

The other end of the coil 47 is adapted to fit over a projection or abutment 48 formed on the integral cross piece 49 of contactor 17 between the arms 50 and 51 of the latter. Contact 17 is provided with end portions 52 and 53 extending in opposite directions from the arms 50 and 51, respectively, at substantially right angles thereto. Said end portions 52 and 53 are of increased width adjacent to the arms 50 and 51, respectively, as indicated at 54 and 55, whereby said end portions are respectively provided with the stepped surfaces 56, 57 and 58, 59 for a purpose hereinafter described.

The respective stationary contacts of the switch may be formed from blanks of like shape and dimensions, and in Fig. 7 I have shown a preferred form of blank for this purpose. Said blank comprises essentially a substantially circular portion 60 having a perforation 61 therein and an arm 62 extending substantially tangentially therefrom. Arm 62 has branches 63 and 64 extending therefrom at a right angle to each other, and extending from the branch 64 at a right angle thereto is a branch 65.

Referring now to Fig. 8, the same shows a stationary contact 66 formed from the blank illustrated in Fig. 7. Contacts 66 formed as shown in Fig. 8 may be located at two of the diagonally opposed corners of the recess 16, as shown in Fig. 1, and contacts 67 each formed from a blank such as illustrated in Fig. 6, but having the arms of said blank bent in the opposite direction, may be located at the other two diagonally opposed corners of the recess 16. In forming a contact such as shown in Figs. 8 and 9 from the blank of Fig. 7, the projection or branch 63 is bent downwardly, along the dotted line 68 at substantially a right angle to arm 62, and the branch 64 is also bent downwardly, along the dotted line 69, at a predetermined angle to the arm 62 (as best illustrated in Fig. 9). The tip 70 of branch 65 is bent at a slight angle along the dotted line 71 (as best illustrated in Fig. 8).

Referring again to Fig. 1, it will be noted that the recess 16 is provided at each of the four corners thereof (as best illustrated at the upper left hand corner thereof) with a communicating notch or recess 72. Said notches 72 extend from the upper surface of base 15 substantially to the bottom of recess 16, each notch being provided with vertical walls 73 and 74 extending at a right angle to each other, and a vertical wall 75 extending at an obtuse angle to the wall 74 and merging into the wall 76 of recess 16. The wall 76 of recess 16 is also preferably provided with a notch 77 extending downwardly for a short distance from the upper surface of base 15.

The recess 16 is preferably provided with straight end walls (shown in dotted lines at 78 and 79 Fig. 1) with which the walls 73 of notches 72 form right angles. The base 15 is provided with a perforation 80 adjacent to each corner of recess 16, and adjacent to each perforation 80 is a cylindrical recess 81. The perforations 80 are respectively adapted to receive the shanks 82 of securing screws which extend upwardly from the lower face of base 15; said shanks 82 being adapted to penetrate the openings 61 in the respective stationary contacts and to take within the tapped openings 83 in terminal plates 84 and 84^a.

The usual wire retaining lugs 85 are arranged on different sides of the respective diagonally opposed pairs of terminal plates 84 and 84^a, and each terminal plate is provided with the usual binding screw 86,—the aforementioned cylindrical recesses 81 being arranged to receive the shanks of said binding screws.

In assembling the contacts 66 upon the base 15, the same are so positioned that the branches 64 extend into notches 72 and branches 63 extend into notches 77, the arms 62 resting upon the upper surface of base 15 with perforations 61 in the former registering with perforations 80 in the latter, whereupon the respective terminal plates 84 and 84^a are secured to the base by the aforementioned screws 82, thus clamping the contacts to the base.

It will be noted that the shape of the stationary contacts is such that upon clamping thereof to the base the branches 64 of each pair to be bridged by contact 17 will tend to approach each other, whereas by reason of the engagement of such branches 64 with the walls 73 of the respective notches 72 the branches 65 at opposite ends of the end wall 78 of recess 16 and branches 65 at opposite ends of the end wall 79 of said recess are normally spaced a predetermined distance apart.

Such positioning of branches 65, in conjunction with the angular arrangement of tips 70 thereof insures proper cooperation of the pairs of stationary contacts with the movable contactor 17; it being noted that sufficient clearance is provided for the branches 64 and 65 to provide for flexure thereof whereby proper wiping engagement of the contact 17 therewith is insured.

Base 15 is also preferably provided with perforations 87 adjacent to each of the binding screws 86, said perforations forming the usual lead-in passages for the circuit wires (not shown). Assuming positioning of the stationary contacts at each of the four corners of the recess 16, the device illustrated in Figs. 1 and 2 is adapted for use as a three-way switch, the usual connector or bus bar 88 being interposed between the securing

70 screws 82 at the upper right and left hand sides of the base (Fig. 1), said connector being located within a suitable recess in the lower face of the base 15 (as best illustrated in dotted lines in Fig. 2).

As will be obvious the device illustrated in Figs. 1 and 2 may be transformed into a single-pole switch by merely omitting the contacts and terminals at the upper and lower left hand ends of recess 16 (Fig. 1) 75 and by omitting the connector or bus bar 88. Moreover, the device illustrated may be wired to provide a single-pole switch without necessitating removal of any of the switch parts.

80 Diametrically opposed slightly elliptical openings 89 are adapted to receive screws or bolts (not shown) for attachment of the base to a suitable support. Said base 15 is also preferably provided with diametrical- 85 ly opposed pillars or projections 90 upon which the metallic housing or cover member 91 (Fig. 2) is adapted to rest, said cover member being provided with the usual insulating lining 92.

90 Projections 90 are perforated, as indicated at 93 to provide for reception of screws or bolts (not shown) which pass through corresponding perforations in the cover member, said bolts taking into suitable nuts 95 located in countersunk recesses in the lower surface of base 15 to provide for rigid attachment of the cover member to said base.

In assembling the parts shown in Fig. 6 100 to provide the unit shown in Fig. 5, the insulating handle 40 is preferably passed upwardly from the bottom of frame 18 and through the opening 25 in the latter until the pivot opening 37 registers with the perforations 34 and 35 in the frame, whereupon 105 the headed pivot pin 36 is inserted and the projecting end thereof pinched or otherwise upset, as indicated in Fig. 5.

Thereupon the movable contactor 17 is assembled with respect to frame 18 in the manner best illustrated in dotted lines in Fig. 4. Thus the contactor 17 is tilted so that the end portion 52 of its arm 50 may be inserted through opening 26 in frame 18 until the lower surface 56 of said end portion engages 115 the horizontal extremity 94 of said opening. With the point 94 as an axis the arm 51 of contactor 17 may be swung in such manner that its end portion 53 clears the horizontal extremity 95 of the opening 27 in the frame. The contactor 17 may then be bodily shifted laterally to cause engagement of the lower surfaces 57 and 59 of its respective end portions with the upper surfaces of end portions 19 and 20 of frame 18. It will be 120 noted that when the contactor 17 is finally assembled on the frame the vertical shoulders 96 and 97 on the end portions of the former are located between the shoulders formed by the horizontal extremities 94 and 130

95 of openings 26 and 27 to prevent lateral shifting of the contactor in either direction.

With contactor 17 assembled in frame 18 in the manner just described the lower end of coiled spring 47 may be dropped over the abutment or projection 48 on said contactor, and the upper end of said coiled spring having the flared tubular member 46 inserted therein may be readily brought into engagement with the rounded edge 44 of projection 43 of the operating lever.

The parts assembled as shown in Fig. 5 may then be attached to base 15 by means of screws 23 and 24, as aforescribed. While I have specifically described one manner of assembling the parts of my improved switch mechanism, other ways of assembling such parts will be apparent to those skilled in the art.

In the modified form of toggle spring actuating mechanism illustrated in Fig. 11 parts corresponding to these aforescribed have been designated by like reference numerals,—it being noted that the form of the movable contactor 17 is substantially like that aforescribed, except that the abutment 48 is preferably omitted, and the adjacent faces of the arms 50 and 51 of contactor 17 are spaced apart only sufficiently to provide clearance for the coiled spring 47 upon oscillation of the latter. Within the lower end of spring 47 is a tubular member 98 having a flared lower end to provide an abutment for said spring,—two sides of said flared end being bent downwardly, as indicated at 99 and 100, to straddle the cross piece 49 of the contactor.

Fitted into the upper end of coiled spring 47 is a member 101, said member having an annular flange resting on said spring and also having a cupped upper surface 103 adapted to receive the rounded end 44 of the operating lever. Member 101 is also provided with a shank 104 normally telescoping to a predetermined degree into the member 98 and adapted for further telescoping movement thereinto incident to oscillation of the operating lever in opposite directions respectively. As will be apparent, the members 98 and 104 act to guide the coiled spring 47 at all times and prevent undue bucking or lateral distortion thereof.

What I claim as new and desire to secure by Letters Patent is:

1. In an electric switch, the combination with recessed insulating base, a frame of substantially inverted U-shape secured by its arms to said base and bridging the recess therein, an opening in each side of said frame adjacent to said base, a substantially U-shaped contactor adapted to oscillate within said recess, said contactor having end portions extending outwardly from the arms thereof at substantially right angles thereto,

the clearance between said openings being at least as great as the distance between the inner end of one of said end portions and the outer end of the other of said end portions whereby said contactor may be assembled 70 with said frame by sequential insertion of said end portions into said openings, and means on said end portions of said contactor for engagement with said frame to prevent lateral shifting of the former with respect to the 75 latter upon assembly thereof.

2. An electric switch comprising a metallic frame substantially of inverted U-shape in cross section, the parallel arms of said frame each having an elongated rectangular opening therein, the end portions of said arms being bent outwardly at substantially right angles thereto at points intermediate the length of the respective openings, a flat sheet metal contactor of substantially U-shape, 85 the parallel arms of said contactor having end portions extending outwardly therefrom, each of said end portions having stepped surfaces, said end portions being insertable sequentially into said openings by tilting movement of said contactor, shoulders between said stepped surfaces arranged to engage the end walls of said openings respectively to prevent lateral shifting movement of said contactor with respect to said frame, an operating lever 90 pivoted to said frame above the aforesigned openings therein, and a coiled compression spring interposed between said lever and said contactor.

3. In an electric switch, the combination 100 with an inverted U-shaped metallic frame, the parallel sides of said frame having foot portions extending outwardly therefrom at substantially right angles thereto, the adjacent portions of each side and foot having a 105 common perforation, a contactor comprising a U-shaped flat metallic stamping, the spaced arms of said contactor having integral outwardly extending end portions provided with stepped lower surfaces, either of said 110 end portions being freely insertable at an angle into one of said perforations to permit subsequent insertion of the other of said end portions into the other perforation, the outer stepped surfaces of said contactor being 115 adapted for engagement with the respective foot portions of the frame to provide for oscillation of the contactor, said contactor being alternately engageable with the opposite walls of said perforations to limit the degree 120 of movement of the former in opposite directions respectively, a plurality of stationary contacts, and means for effecting snap movement of said contactor into and out of engagement with said contacts.

4. As an article of manufacture, an electric switch contactor comprising a flat metallic stamping of substantially U-shape, the arms of said contactor having integral end portions extending outwardly therefrom at 130

substantially right angles thereto, each of said end portions having a plurality of stepped surfaces, the respective outer stepped surfaces providing pivot portions for engagement with a suitable support, and the shoulders formed by said stepped surfaces being adapted to prevent endwise movement of said contactor with respect to said support.

5. As an article of manufacture, an electric snap switch contactor comprising a substantially U-shaped flat metallic stamping, the arms of said contactor having integral end portions extending outwardly therefrom at substantially right angles thereto, each of said end portions having a pair of lower surfaces offset from each other, the opposite extreme surfaces providing pivot portions for suspension of said contactor from a suitable support, and an abutment projection intermediate the arms of said contactor and integral therewith.

6. In an electric snap switch, the combination with a molded insulating base having a substantially rectangular recess in the upper surface thereof, vertical notches communicating with said recess at the four corners of the latter, stationary contacts secured to the upper surface of said base and having depending arms engaging the adjacent vertical walls of each pair of notches to limit the degree of movement of said arms toward each other, said arms each having a branch extending outwardly from said notches and the branches of each pair having portions flared outwardly from each other, an inverted U-shaped frame mounted on said base, a contactor comprising a flat sheet metal stamping of substantially U-shape, the arms of said contactor having stepped end portions extending outwardly therefrom at substantially right angles thereto, the sides of said frame having aligned perforations within which the end portions of said contactor are insertable sequentially to provide for pivotal connection thereof with said frame, and means comprising a coiled compression spring and actuating means therefor to effect snap movement of said contactor into and out of engagement with said pairs of stationary contacts.

55 7. In an electric snap switch, in combination, a frame comprising a metallic stamping having base portions and parallel side portions integral with said base portions, all parts of each side portion being located in a common plane, said side portions being respectively provided with relatively large aligned openings, a movable switch contactor, said contactor comprising a flat sheet metal member of substantially U-shape, the arms of said U-shaped member having end portions arranged at substantially right angles thereto, and certain of said end portions being provided with a plurality of lower edge surfaces arranged in stepped relation to each

other, one of said end portions being fully insertable into one of said side openings to provide for alinement of the other end portion with its corresponding side opening upon tilting of said U-shaped member, whereby the last mentioned end portion and the uppermost stepped surface of said first mentioned end portion may be brought into pivotal engagement with the respective side openings upon subsequent edgewise movement of said U-shaped member. 75

8. In an electric snap switch, in combination, a frame comprising a metallic stamping having base portions and parallel side portions integral with said base portions, all parts of each side portion being located in a common plane, said side portions being respectively provided with relatively large aligned openings, a movable switch contactor, said contactor comprising a flat sheet metal member of substantially U-shape, the arms of said U-shaped member having end portions arranged at substantially right angles thereto, each of said end portions being provided with a pair of lower edge surfaces arranged in stepped relation to each other, either of said end portions being fully insertable into one of said side openings to provide for alignment of the other end portion with its corresponding side opening by tilting of said U-shaped member, whereby the uppermost stepped surfaces of the respective end portions may be brought into pivotal engagement with the respective side openings upon subsequent edgewise movement of said U-shaped member, and the shoulders formed between the stepped surfaces of each of the aforementioned pairs being adapted to restrain said U-shaped member against further edgewise movement in either direction. 100

9. In an electric snap switch, in combination, a frame comprising a metallic stamping having base portions and parallel side portions integral with said base portions, all parts of each side portion being located in a common plane, said side portions being respectively provided with relatively large aligned openings, a movable switch contactor, said contactor comprising a flat sheet metal member of substantially U-shape, the arms of said U-shaped member having end portions arranged at substantially right angles thereto, each of said end portions being provided with a pair of lower edge surfaces arranged in stepped relation to each other, either of said end portions being fully insertable into one of said side openings to provide for alignment of the other end portion with its corresponding side opening by tilting of said U-shaped member, whereby the uppermost stepped surfaces of the respective end portions may be brought into pivotal engagement with the respective side openings upon subsequent edgewise movement of said U-shaped member, an actuating lever pivot-

ed to said frame, and a compression spring interposed between said lever and said U-shaped member to hold the latter in assembled relation to the frame and to effect snap movements of said member from each extreme position to the other upon movement of said actuating lever in opposite directions respectively.

10. In a snap switch, the combination with a stamped sheet metal bracket having substantially parallel side portions, said side portions having aligned perforations forming closed bearings, of a flat punched sheet metal member of substantially bail form, the ends of 15 said bail member each having a plurality of lower edge surfaces arranged in stepped relation to each other and being insertable into said bearings by sequential tilting and edge-wise movements of said member, an actuating 20 member pivotally supported by said bracket above said bail member, and a compression spring interposed between said actuator and said bail member to retain the latter in pivotal engagement with said bracket and to 25 effect snap movement thereof upon movement of said spring in either direction across the pivotal center of said bail member.

11. In a snap switch, the combination with a stamped sheet metal frame having parallel 30 sides, said sides having perforations forming closed bearings, of a flat punched sheet metal plate of substantially U-shape, the arms of said U-shaped plate having integral angular projections adapted for sequential 35 insertion into said bearings by tilting and edge-wise movements of said plate with respect to said frame, said projections each having offset lower edge portions providing shoulders to limit edge-wise movement 40 of said plate after assembly of the parts, an actuating lever pivotally supported by said frame above the pivotal center of said plate, and means comprising a compression spring interposed between said lever and said plate 45 to effect snap movements of the latter to alternate extreme positions upon opposite movements of said actuating lever.

12. In a snap switch, the combination with a stamped sheet metal frame having parallel 50 sides, said sides having perforations forming closed bearings, of a flat punched sheet metal plate of substantially U-shape, the arms of said U-shaped plate having integral angular projections adapted for sequential insertion 55 into said bearings by tilting and edge-wise movements of said plate with respect to said frame, said projections each having offset lower edge portions providing shoulders to limit edge-wise movement of said plate 60 after assembly of the parts, an actuating lever comprising a flat punched sheet metal plate pivotally supported by said frame above the pivotal center of said first mentioned plate and at right angles to the latter, 65 means comprising a compression spring in-

terposed between said lever and said first mentioned plate to effect snap movements of the latter to alternate extreme positions upon opposite movements of said actuating lever, and projections integral with said second mentioned plate for alternate engagement with said frame to limit movement of said lever in opposite directions respectively. 70

In witness whereof, I have hereunto subscribed my name.

GEORGE J. MEUER. 75
